(57) **CLAIM**

We claim the ornamental design for a model vehicle wing assembly, as shown and described.

DESCRIPTION

FIG. 1 is an upper, left, front perspective view of a model vehicle wing assembly showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof; and,

FIG. 8 is a lower, left, rear perspective view of the model vehicle wing assembly.

In the drawings, the broken lines illustrate portions of the model vehicle wing assembly that form no part of the claimed design.
